WILLIAM F. FORCE, OF FLATBUSH, NEW YORK, ASSIGNEE OF ONE-HALF TO ERNEST B. LATHAM, OF BROOKLYN, NEW YORK.

SAFETY APPLIANCE FOR ELECTRICAL INSTALLATIONS.

1,076,754.

Specification of Letters Patent.

Patented Oct. 28, 1913.

Application filed January 24, 1912. Serial No. 673,166.

To all whom it may concern:

Be it known that I, WILLIAM F. FORCE, a citizen of the United States, residing at Flatbush, Kings county, State of New York, have invented certain new and useful Improvements in Safety Appliances for Electrical Installations, of which the following is a full, clear, and exact description.

My invention relates to safety appliances for electrical installations. With thermal cut-outs, as at present made, in some instances, it is easy for an unauthorized person to substitute a cut-out of a large capacity for a cut-out of a smaller capacity, thereby removing from the installation the desired protection. It is further possible to alter the fusible member of the cut-out, without danger of detection, by substituting for a fuse strip of one capacity, a conductor of larger capacity or one which will not act properly as a fuse. It is further possible to connect the two terminals of an inclosed fuse by an external strip, which is a conductor which does not readily act as a fuse, or by means of a fuse strip of large capacity. It is further possible with some devices, such as those known as Edison plugs, to insert a piece of metal in the socket, which will connect the two line terminals, and thus complete the circuit independently of the fuse carrier. It is further possible to easily alter the fuse socket of such devices so that an electrical connection will be made irrespective of the fuse strip carrier.

My invention has for its object to make it practically impossible to do any and all of these things.

My invention further has for its object to produce a device, in which connection cannot be made with the circuit at one end of an inclosed fuse until after a good connection has been made with the other terminal of the inclosed fuse.

My invention further has for its object to provide a device in which the danger due to live conductors or contacts is practically eliminated.

My invention further has for its object to provide a support which incloses the inclosed fuse so as to prevent danger if the inclosed fuse explodes so as to burst its casing.

The following is a description of an embodiment of my invention, reference being had to the accompanying drawings, in which,

Figure 1 is a panel board having a series of appliances embodying my invention. Fig. 2 is a partial section on the line $\alpha-\alpha$ Fig. 1. Fig. 3 is a partial section on the line $\gamma-\gamma$ Fig. 1.

Referring more particularly to the drawings, 1 is the base of a panel board having bus bars $2' 2^2 2^3$ connected to the main circuit.

3—3' are terminals of one branch circuit connected to said bus bars.

4—4' are terminals of the second branch circuit of larger capacity connected to said bus bars.

Mounted upon the panel board are fuse holders, each consisting of a porcelain base 5 provided with a bore 6 extending partly therethrough, the inner ends 6' of the bores being slightly smaller than the outer portions.

The bases over the ends of the terminals 3—3' are the same in all respects. The bases over the ends of the terminals 4—4' are the same as each other in all respects but differ from the bases over the terminals 3—3' as hereinafter pointed out. The pairs of similar bases are preferably formed integral and are secured to the panel board by screws 3^2 and 4^2 . The terminals 3—3' and 4—4' are provided at their ends with holes or sockets 7, those of the terminals 3—3' being smaller than those of the terminals 4—4'.

These holes 7 are preferably screw-threaded. They are each in line with the axis of the bore of the corresponding base, which bores at their inner ends are closed by closures 8 perforated with holes 9 in line with the holes 7. The bases are provided with recesses 10 on one side, through which pass conductors 11, secured to binding posts 12, and terminating in connecting rings 13, which rest upon flanges formed on the bases at the outer ends of the bores. In case the holes 7 are screw-threaded, the inner surface of the rings 13 are preferably not screw-threaded.

14, 14' are inclosed fuses, by which I mean inclosed thermal cut-outs of any suitable

tv ., preferably those with a fusible metallic conductor 15 within them. 16 is the casing. 17 is a metallic plug inserted in one end of the casing 16 and secured therein by 5 a rivet 18. 19 is a metallic projection extending from the plug 17 and adapted to fit the socket or hole 7 formed in one or the other of the branch conductors 3, 3' or 4, 4'. The fuses of the proper capacity for the 10 branch circuit 4, 4' have larger plugs 19 than the fuses of the proper capacity for the circuit 3, 3'. The projections of the larger size fuses are bored out internally as at 20 so as to make it impossible to machine a 15 larger plug down to the size of a smaller plug, it being obvious that with this arrangement, the reducing of the larger plug to the size of the smaller plug would cut away the metal entirely. The holes in the 20 extensions may be filled with some soft metal, as shown, to increase the conductivity. The outer end of the inclosed fuse is provided with a ferrule 21 having a flange 22. This flange is adapted to engage the 25 ring 13 when the inclosed fuse is in place. If the ferrule 21 and the ring 13 are not provided with screw threads, or other means for holding the inclosed fuse in place, the 30 projections 19 and the holes 7 are provided with screw threads for that purpose, and the construction last referred to, namely, the screw-threaded extension and hole, is the preferable construction. The fuse strip or member 15 within the casing 16 is connected 35 to the plug 17 and the ferrule 21, so as to form a good electrical connection between them. A cap 23 made of insulation, such as glass or porcelain, is cemented or otherwise secured to the ferrule 21 so that when the 40 inclosed fuse is being put into place, it is unnecessary to touch any live contact. For clearness the cap 23 is omitted in Fig. 1.

The enlargement in the bore extends to 45 slightly below the center of the inclosed fuse, so that if the inclosed fuse bursts there will be ample space for the gases to escape without bursting the base. The inner part 6' of the bore fits the inner end of the inclosed fuse closely so as to prevent the insertion 50 of any thin piece of metal, by which an unauthorized person might attempt to bridge the two terminals of the inclosed fuse. The hole 9 through the inner end 8 of the fuse support is of such size as to just permit the 55 passage of the projection 19 which engages the conductor 3 or 4. The fuse 14' has a smaller projection than the fuse 14, which latter is of the larger capacity. The size of the hole 9 at the inner end of the bore for 60 the small capacity fuse will not permit the passage of the extension of the larger capacity fuse, and cannot be easily reamed out so as to permit that passage, since reaming it out would probably break the porcelain

base. It, therefore, not only prevents the 65 insertion of a large capacity fuse, but prevents access to the end of the conductor 3' for the purpose of reaming out the hole therein, which would also be necessary if the larger capacity fuse was to be inserted in the 70 circuit of smaller capacity. The construction has the advantages above referred to, inasmuch as the inner end 8 of the base, which, except for the opening 9 therein, separates the inner terminals 3 or 4 from the 75 outer terminal 13, makes it difficult to connect the two line terminals, except by substituting some device, which is especially made to be substituted, and the terminals of the inclosed fuse cannot be bridged because 80 the plug 17 is an internal plug, and the inner end of the bore 6 is of such size as to prevent the insertion of the inclosed fuse casing if a bridging member has by any means been secured to the outside thereof. 85 Moreover, if it were attempted to connect a bridging member with the bottom of the plug 17, it would lift the flange 22 so that it would no longer make contact with the ring terminal 13. A conductor cannot be 90 satisfactorily substituted for a blown fuse strip within the inclosed fuse casing, since the fuse strip does not penetrate the plug 17. For this reason, even if it were possible to solder one end of a substituted conductor to the ferrule 22, it would be impossible to make a proper electrical connection between the other end and the plug 17. The insulating cap 23, however, not only enables the fuse to be inserted without handling a 100 live part, but in and of itself prevents the insertion in the fuse casing of a conductor in lieu of proper fuse, by inclosing the upper end of the ferrule 22.

The extension 19 makes engagement with 105 the conductor 3 or 4, prior to the engagement of the flange 22 with the ring 13. Contact, therefore, is not made at the outer end of the inclosed fuse until it is fully in place. The inclosing wall forming the bore 110 6 surrounds the inclosed fuse, and affords protection against fire in case the casing of the fuse bursts, and yet, on account of its enlarged outer portion, permits the escape 115 of gases due to the rupture of the fuse strip. The inclosed fuses, having the proper sized extensions to engage the conductors 3 or 4, cannot be inserted into the casing so as to complete the electrical circuit, unless they are of the proper length, that is, a fuse 120 which is too long for the intended service will not make electrical contact with the ring 13 in a base intended for a shorter fuse. A fuse intended for a short base will not make electrical contact between the extension 19 and the conductor 3 or 4, if inserted 125 in a base intended for a longer fuse. I prefer to make the projections 19 on all fuses

5 screw-threaded in the same direction, and to rely upon the differences in size of the projections in order to prevent the exchange of inclosed fuses of the same length, or of 10 different capacities, since if right and left handed screws of the same size were used to distinguish between fuses of different capacities, the thread on the extension belonging to the fuse of the larger capacity might 15 be re-cut so that the fuse could be used on a circuit where a fuse of a smaller capacity only should be used.

According to the requirements of the Board of Underwriters at the present time, 15 the invention is particularly useful in connection with fuses of 30 amperes capacity and under. According to present requirements, all inclosed fuses of 30 amperes and under are of the same length and of the same diameter. For most purposes it is sufficient 20 to divide these fuses into four groups, namely, those of a capacity carrying from one to six amperes inclusive; those of a capacity carrying from seven to twelve amperes inclusive; those of a capacity carrying 25 from thirteen to twenty amperes inclusive; those of a capacity carrying from twenty-one to thirty amperes inclusive. If the inclosed fuses of each group are constructed 30 according to the above description, and have their inner terminals provided with extensions of different sizes, one size for each group, such a classification will be sufficient 35 for ordinary purposes.

35 The construction above described is the preferred form. It will be seen, however, by those skilled in the art, that my invention permits of various modifications without departing from the spirit thereof, or the scope 40 of the appended claims.

What I claim is:

1. In a device of the character described, 45 the combination of a fuse support having a bore therein, a conductor constituting a line terminal having a socket concentric with said bore and located near one end thereof, said support having an insulating partition between the end of said bore and said conductor, and a perforation through said partition in line with said socket, a second line 50 terminal located at the other end of said bore, and an inclosed fuse consisting of an insulating casing having at one end a metallic plug provided with an extension adapted 55 to pass through said hole and engage said socket, and having at the other end a fuse terminal adapted to engage said second line terminal, and a fuse strip inclosed within 60 said casing and connected to said fuse terminal and plug, said bore fitting a part of said insulating casing closely.

2. In a device of the character described, 65 the combination of a fuse support having a bore therein, a conductor constituting a line

terminal having a socket concentric with 65 said bore and located near one end thereof, said support having an insulating partition between the end of said bore and said conductor and a perforation through said partition in line with said socket, a second line 70 terminal located at the other end of said bore, and an inclosed fuse consisting of an insulating casing having at one end a metallic plug provided with an extension adapted 75 to pass through said hole and engage said socket, and at the other end a fuse terminal adapted to engage said line terminal, said second external line terminal having a contact surface lying in a plane at right angles to the axis of said bore, and said outer fuse 80 terminal having a contact surface extending at right angles to the axis of said fuse and adapted to engage said first mentioned contact surface, part of said bore fitting said insulating casing closely. 85

3. In a device of the character described, 90 the combination of a fuse support having a bore therein, a conductor constituting a line terminal having a socket concentric with said bore and located near one end thereof, said support having an insulating partition between the end of said bore and said conductor and a perforation through said partition in line with said socket, a second line 95 terminal located at the other end of said bore and having a contact surface at substantially right angles to said bore, and an inclosed fuse having a casing within one end of which is a metallic plug having an extension adapted to pass through said hole and 100 engage said socket and at the other end of which is a terminal adapted to engage said surface of said second line terminal, said socket and extension having engaging screw-threads. 105

4. In a device of the character described, 110 the combination of a fuse casing, a metallic plug in one end thereof having an external projection, a ferrule on the other end thereof, and a fuse strip connecting said plug and said ferrule, said ferrule having a lateral projection forming a contact surface at right angles to the axis of said fuse.

5. In a device of the character described, 115 the combination of a fuse casing, a metallic plug in one end thereof having an external projection, a ferrule on the other end thereof, and a fuse strip connecting said plug and said ferrule, said ferrule having a lateral projection forming a contact surface at right 120 angles to the axis of said fuse, and a cap of insulation secured to said ferrule above said lateral projection.

6. In a device of the character described, 125 the combination of a base having a bore, enlarged near its outer end, a conductor having a socket adjacent to the inner end of said bore, a line terminal adjacent to the

other end of said bore, an inclosed fuse having an insulating casing closely fitting the inner end of said bore and spaced apart from the surface of the outer portion thereof and having a metallic extension engaging said socket and forming a terminal of said fuse, and another terminal engaging

said line terminal, said base having a perforated insulating partition at the inner end of said bore.
